GAME CARRIER

Sondre S. Reishus, Mott, N. Dak.

Application May 31, 1944, Serial No. 538,152

4 Claims.

(Cl. 224—7)

This invention relates to a hunter's game carrier and has for the primary object, the provision of a device of this character which may be worn over ordinary hunting garments to permit game killed to be conveniently carried along with hunting accessories without interfering with the normal movement of the hunter.

Another object of the invention is the provision of an apron-like panel preferably of waterproof material and provided with attaching means for the securing of the panel across the back and over the hips and at the waistline of the hunter and includes means for suspending thereon birds and other game to prevent contact thereof with the garments of the hunter or from interfering with movements of the hunter's body, arms or legs, or with the hunter quickly taking a shooting position and locates the hunting accessories, such as the ammunition in convenient reach of the hunter.

With these and other objects in view as will become apparent as the description proceeds, the invention consists in certain novel features of construction, combination and arrangement of parts as will be hereinafter more fully described and claimed.

For a complete understanding of my invention, reference is to be had to the following description and accompanying drawing, in which—

Figure 1 is a view in elevation with parts broken away illustrating a hunter's game carrier constructed in accordance with my invention.

Fig. 2 is a fragmentary sectional view taken on the line 2—2 of Fig. 1.

Fig. 3 is a fragmentary sectional view taken on the line 3—3 of Fig. 1.

Fig. 4 is a detail sectional view taken on the line 4—4 of Fig. 1.

Referring in detail to the drawing, the numeral 5 indicates an elongated garment protecting panel and provided with rounded corners and composed preferably of waterproof material or fabric and of double thickness as shown in Figs. 2 and 3 of the drawing. To construct the panel of double thickness layers of waterproof material 6 are brought together and have the edges thereof turned inwardly as at 7 and stitched together as at 8, the stitching extending entirely about the edges of the panel 5 also longitudinally thereof with the stitching interrupted at opposite ends of the panel cooperating with stitching 9 and forming a guideway 10 to freely receive a waist belt not shown. The guideway 10 is located a limited distance below the upper edge of the panel with that portion of the panel provided

with series of stitching 11 for strengthening or reinforcing the upper portion of the panel to which is secured spaced tabs 12 carrying rings or like elements 13. The rings 13 are engaged by snap fasteners 14 connected to the ends of a sectional neck strap 14'. The sections of the neck strap are detachably and adjustably connected by a suitable buckle 15. It is preferable that the buckle 15, snap fasteners 14 and rings 13 be of an extremely small size so as to present a neat appearance as well as not interfering with the person wearing the device.

On the lower portion of the panel 5 and extending to the end edges thereof are pockets 16 fully open along their upper longitudinal edges whereby hunting accessories, such as ammunition may be conveniently arranged within the pockets. The pockets 16 are formed by applying to the panel 5 layers of material stitched to the outer layer that goes to make up the panel 5 as shown at 17. The layers of material that form the pockets may have edges thereof turned inwardly with the edges of the layers of material which form the panel and be secured in place by the stitching 8. The layers of material forming the pockets also may have rows of stitching 18 adjacent to the mouths of the pocket for the purpose of reinforcement.

30 A plurality of game suspension straps 19 each including a noose 20 are provided on the panel 5. The straps further include loop portions 21' arranged within the belt guide 10 between the layers of material that make up the panel 5 and are stitched to both layers both vertically and 35 longitudinally of the panel so that the waist belt may also extend through the loop portions of the straps when extended through the guideway 10 of the panel placing the loads carried by the straps onto the waist belt relieving to a great extent load strain on the panel 5 as well as on the 40 neck strap 14'.

The free ends of the straps 19 have secured thereto rings 21 through which the straps pass to form the nooses 20 and slidably on the straps within the nooses are rings 22 that act to prevent the rings 21 from moving off of the straps and also may be used as finger pieces for quickly adjusting the size of the nooses and thereby facilitate the application of the nooses to the game and the adjustment thereof on the game. The rings 22 will greatly assist the hunter in adjusting the size of the nooses when the straps become wet or when dried after being wet and becoming stiff.

It is preferably that the length of the straps

be such that when game is applied thereto as indicated in dotted lines in Fig. 1, the major portion of the game will lie against the panel 5 and be prevented from contacting the garments of the hunter. This will prevent the garments from becoming soiled from the game and will arrange the game so as to have a minimum of effect on the normal movements of the hunter, leaving the hunter's arms and legs free of interference in that they may quickly assume shooting position.

Any type of waist belt may be used in conjunction with the apron that will pass freely through the guideway 10 and loop portions 21' of the straps. In applying this device to a hunter the neck strap is placed over the head and across the shoulders with the apron extending across the hunter's back and over the hips, the waist belt is then fastened about the waist of the hunter with the straps 14' engaging the neck under the chin of the hunter. It will be seen that the game carrying straps 19 are then located in rear of the hunter with the pockets 16 at the hips of the hunter in convenient reach of the hands. Game as killed may readily be placed in the nooses of the straps and supported in a suspended position with the game resting against the panel 5 and thereby prevented from contacting the garments of the hunter. A large extent of the load of the game carried by the straps is borne by the waist belt relieving strain on the hunter's neck of the greatest proportion of the load. The game being arranged at the rear or back of the hunter leaves the legs and arms perfectly free for normal actions and for movements into shooting position.

While I have shown and described the preferred embodiment of my invention, it will be understood that minor changes in construction, combination and arrangement of parts may be made without departing from the spirit and scope of the invention as claimed.

Having thus described my invention, what I claim is:

1. In a game carrier for use by hunters, an elongated panel, a longitudinal belt guideway extending through said panel, a plurality of game suspension straps having loops at the upper ends thereof positioned in said guideway, a waist encircling belt positioned in said guideway and through said loops, the lower end of each of said game suspension straps being provided with a fixed ring with said strap folded through said ring forming a noose on the lower end of said strap, and a second ring slidably positioned around said strap within said noose.
2. In a game carrier for use by hunters, an elongated panel, a longitudinal belt guideway extending through said panel, a plurality of laterally extending openings in said guideway, a plurality of game suspension straps positioned through said openings, loops on one end of said straps within said guideway, a waist encircling belt positioned through said guideway, and said loops, a fixed ring on the other end of each of said straps with said strap folded through said ring forming a noose thereon, and a slidably member on said strap inside of said noose.
3. In a game carrier for use by hunters, an elongated panel, a longitudinal belt guideway extending through said panel, a game suspension strap having a loop at its upper end, said loop being positioned in said guideway, a waist encircling belt positioned through said guideway and said loop, a noose on the other end of said strap, and a slidably ring on said strap within said noose.
4. In a game carrier for use by hunters, an elongated panel, a longitudinal belt guideway extending through said panel, a game suspension strap having a loop at its upper end, said loop being positioned in said guideway, a waist encircling belt positioned through said guideway and said loop, a ring member secured to the lower end of said strap, said strap being folded through said ring to form a noose, and a slidably member secured around said strap within said noose.

SONDRE S. REISHUS.
